UNITED STATES PATENT OFFICE

110,064

DESIGN FOR A SERVICE BAR BACK COUNTER

Giraud W. Behrel, Chicago, Ill., assignor to The Brunswick-Balke-Collender Company, Chicago, Ill., a corporation of Delaware

Application December 11, 1937, Serial No. 73,531

Term of patent 3½ years

To all whom it may concern:

Be it known that I, Giraud W. Behrel, a citizen of the United States, residing in the city of Chicago, in the county of Cook, State of Illinois, have invented a new, original, and ornamental Design for a Service Bar Back Counter, of which the following is a specification, reference being had to the accompanying drawing, forming a part thereof.

In the drawing:

The figure is a perspective view of a service bar back counter showing my new design.

I claim:

The ornamental design for a service bar back counter as shown.

GIRAUD W. BEHREL.
